(57) **CLAIM**

The ornamental design for a glassware with embedded chakra stone, as shown and described.

DESCRIPTION

FIG. 1 is a perspective front right side view of glassware with embedded chakra stone, showing my new design.

FIG. 2 is a perspective front view of glassware with embedded chakra stone.

FIG. 3 is the perspective back view of the glassware with embedded chakra stone.

FIG. 4 is the right side view of the glassware with embedded chakra stone.

FIG. 5 is the left side view of the glassware with embedded chakra stone.

FIG. 6 is the top view of the glassware with embedded chakra stone; and,

FIG. 7 is the bottom view of the glassware with embedded chakra stone.

The broken lines in the drawings depict portions of the glassware with embedded chakra stone that form no part of the claimed design.
